Chicago, Ill., 60639

Filed May 22, 1967, Ser. No. 7,222

Term of patent 14 years

(Cl. D26—14)

FIG. 1

FIG. 3

FIG. 2

FIG. 1 is a front view of a television antenna showing my new design;

FIG. 2 is a rear perspective view thereof, with the broken line representation of the foliage omitted for ease of illustration;

FIG. 3 is a perspective view as seen from the left of FIG. 2. The dominant features of my design reside in the portions shown in full lines.

I claim:

The ornamental design for a television antenna, as shown and described.
